BLADE HOLDER

Henry Huber, Pontiac, Mich.

Application March 26, 1936, Serial No. 70,913

1 Claim. (Cl. 30—162)

The present invention pertains to a blade holder of the type particularly adapted for holding safety razor blades.

The primary object of the present invention is 5 to provide a holder for razor blades which is adapted for use in holding razor blades of popular makes, either of the type having double cutting edges or single cutting edges, and which is so constructed that a blade may be supported in 10 an endwise projecting position adapting it for use as a cutting instrument such as a knife, in a position wherein the entire cutting edge along one side thereof is exposed so that the device may function as a scraping implement, and in a 15 position wherein the blade is entirely concealed or housed so that it may be carried in a person's pocket, without doing any damage.

Another object of the present invention is to 20 provide a blade holder embodying a pair of yieldably spaced apart walls and means for supporting a razor blade between such walls so that by clamping the walls together they frictionally engage the blade to hold the same against movement with respect to the body, the means for 25 supporting the blade being guided in movement with respect to the body so that the blade may be moved, when the clamping means is released, to positions adapting the device for service as different kinds of tools.

With the above and other ends in view the 30 invention is more fully disclosed with reference to the accompanying drawing, in which

Figure 1 is a side elevation;

Fig. 2 is a vertical section;

35 Figs. 3, 4 and 5 are sections taken respectively on the lines 3—3, 4—4 and 5—5 of Fig. 2, and

Fig. 6 is a side elevation illustrating an alternative position of the blade.

Like characters of reference are employed 40 throughout to designate corresponding parts.

The numerals 1 and 2 designate side walls integrally united by a portion 3. The portion 3 supports the side walls 1 and 2 slightly spaced apart and embodies sufficient flexibility to permit 45 a small amount of springing of the side walls with respect to each other. The side walls are formed with parallel slots having straight portions 4 extending substantially in the direction of the length of the walls 1 and 2 and with portions 50 5 extending obliquely to the portions 4. A plate 6 is disposed against the outside face of the wall 1 and has a pair of spaced apart studs 7 and 8 projecting through the slots in the walls 1 and 2. A razor blade 9, illustrative of any popular make 55 of razor blade, has apertures 10. The blade is

supported between the walls 1 and 2 by the studs 7 and 8. The stud 7 is screwthreaded as illustrated to receive a thumb nut 11.

As illustrated in Fig. 1 the studs 7 and 8 are disposed in the straight portion 4 of the slots 5 and thus support the blade 9 in a position projecting endwise from the walls 1 and 2. By tightening the thumb nut 11 the walls 1 and 2 are drawn into frictional engagement with the sides of the plate to hold the same in the position 10 shown. The blade is thus supported in a position adapting the device for uses corresponding to those of a knife.

By loosening the thumb nut 11 the plate 6 and blade may be moved with respect to the side walls 15 1 and 2 and by moving the plate and blade so that the studs 7 and 8 rest in the oblique portions 5 of the slots the entire side edge of the blade is exposed as illustrated in Fig. 6. When the blade has been moved to the position illustrated in Fig. 6 the thumb nut 11 is again tightened 20 and the blade is frictionally held in this position adapting the device for use as a scraping implement.

By positioning the studs 7 and 8 in the other 25 ends of the straight portions 4 of the slots to those in which they are illustrated in Fig. 1, the blade will be placed in a position where it is entirely concealed between the walls 1 and 2 so that the device may be carried in a person's 30 pocket.

From the foregoing it becomes apparent that 35 the blade 9 may be moved to different positions of adjustment wherein it functions as different kinds of tools without the necessity of completely 40 removing the blade. Furthermore such adjustments can be made without the necessity of the person making the same actually touching the blade inasmuch as the thumb nut 11 and plate 6 may be grasped to apply the pressure necessary 45 to move the blade.

Although a specific embodiment of the invention has been illustrated and described it will be understood that various changes may be made within the scope of the appended claim without 50 departing from the spirit of the invention and such changes are contemplated.

What I claim is:—

A device of the character described comprising 55 a body having spaced apart side walls, a blade, means for guiding movement of said blade with respect to said body, and means for clamping said side walls against said blade to hold it in positions of adjustment, said guiding means comprising parallel slots in opposed side walls of said 60

body and means carried by the blade and movable in said slots, said slots having portions disposed whereby they support the blade projecting end-wise from said body, portions disposed whereby they support the blade entirely concealed within the body, and portions disposed whereby they

support the blade with one side edge angularly exposed, the several portions of said slots being connected whereby the guiding means carried by the blade may be continuously moved from one position to another.

HENRY HUBER.
